BITUMINOUS ASH REMOVER FOR UNDER-
FEED STOKERSHaskell C. Carter, Portland, Oreg., assignor to
Iron Fireman Manufacturing Company, Port-
land, Oreg.

Application June 18, 1935, Serial No. 27,195

7 Claims. (Cl. 110—45)

This invention relates generally to underfeed stokers, and particularly to bituminous ash removers therefor.

The main object of this invention is the construction of an ash remover for bituminous underfeed stokers which will so affect the manner in which the coal is consumed that it will reduce the tendency to form clinkers, thereby simplifying the problem of removing the incombustibles from the combustion zone.

The second object is to provide an improved form of ash remover which incorporates a means for delivering air to a larger area of the burning surface than is ordinarily possible and at the same time make it possible to vary the rate of flow of said air to various portions of the fuel bed.

The third object is to construct an ash remover which makes possible the use of small discharge openings for the ashes at the same time eliminating shearing points between the ash ports and the ash removal arms with the consequent reduction of noise which accompanies clinkers crushing and also avoiding the difficulty of having clinkers wedged between the ash removal arms and the ash plate.

The fourth object is to so construct the ash remover that the coal will be burned over a relatively large area at a temperature below the fusing point of the incombustibles bringing about a condition which is extremely favorable to the mechanical removal of the ashes.

The fifth object is to construct a retort and tuyère assembly together with the surrounding ash rings with a relatively small inside tuyère diameter where the green coal enters the fuel bed for the purpose of breaking up any coke columns which might form and also to increase the active burning area for the coal.

The sixth object is to provide a special form of ash ring adapted to be selectively rotated to various positions for the purpose of varying the ratio of the air flow to the inner part of the retort with relation to the flow to an outer portion of the retort and also to obtain a regulation for the pressure of the air flowing toward the outer portion of the retort.

The seventh object is to construct the portion of the tuyère which is subjected to the most intense heat, as well as the projecting arms, in the form of an integral casting of a high alloy heat resisting steel and to so mount same that it may be easily replaced if necessary.

I accomplish these and other objects in the manner set forth in the following specification as

illustrated in the accompanying drawings, in which:

Fig. 1 is a side elevation of a complete stoker showing the ash removal worm exposed and the fuel feed duct broken away in section to disclose the fuel feed worm and showing the outline of the furnace in dotted lines.

Fig. 2 is a vertical section taken along the line 2—2 in Fig. 1.

Fig. 3 is a fragmentary vertical developed section taken along the line 3—3 in Fig. 2.

Fig. 4 is a plan of the tuyère and ash removing section with portions broken away in horizontal section.

Fig. 5 is a vertical section taken along the line 5—5 in Fig. 4 showing the ring in its lowest adjusted position.

Fig. 6 is a section taken along the line 6—6 in Fig. 5.

Fig. 7 is a section taken along the line 7—7 in Fig. 2.

Similar numbers of reference refer to similar parts throughout the several views.

Referring in detail to the drawings, there is shown a hopper 10 from which coal is conveyed through a coal tube 11 by means of a coal feeding worm 12 which is driven from a motor 13 through gearing contained within a transmission casing 14. The coal tube 11 terminates in a retort 15 which is surrounded by the plenum chamber walls 16. A floor plate 17 forms the bottom of the plenum chamber 18, while the side walls 16 merge into the horizontal top 19 which extends into the retort 15.

A circular plate 20 is mounted on the top 19 and secured thereto by means of bolts 21. Openings 22 are formed through the top 19 and the plate 20 for the upward passage of air from the plenum chamber 18 to which air is supplied through an air duct 23 by a fan (not shown). Rotatably mounted on the plate 20 is the outer tuyère wall 24, whose horizontal flange 25 rotates upon the plate 20 and extends beyond the outer edge of the plate 20. A toothed ring 26 is secured to the underside of the extending portion of the flange 25 and meshes with the inclined ash removing worm 27 which occupies the ash removing duct 28 and is driven from its upper end through a universal joint (not shown) by means of a sprocket wheel 29 which is connected by the chain 30 to the power takeoff sprocket wheel 31 on the side of the transmission casing 14. The upper side of the end 32 of the ash removing duct 28 is cut away to expose the worm 27 to the toothed ring 26 and to the ashes which fall down.

wardly around the outside of the plenum chamber 18.

Projecting inwardly from the outer tuyère wall 24 are the spokes 33 which connect with the circular inner tuyère wall 34, whose lower end 35 extends downwardly into the opening 36 formed in the center of the plate 20. The interior of the wall 34 registers with the interior of the retort 15. The end 35 preferably does not engage the wall of the opening 36 or the top 19. The top side 37 of the tuyère wall 34 slopes downwardly from its outer and inner edges to an intermediate line 38.

Supported on the top side 37 and on the top 15 of the outer tuyère wall 24 is the element 39, from the top face of which projects a plurality 20 of radial arms 40, the underside of each of which has formed therein a channel 41 through which air can pass upwardly from the space 42 through 25 the opening 43 and be discharged downwardly from the arms 40. Within the wall 34 are formed the air outlets 45, the top side of which is formed by the element 39. The outer portion 46 of the element 39 rests upon the wall 24 in whose upper edge are formed the notches 47 through which air can pass from the space 42 to the outer side of the wall 24 without passing 30 through the arms 40.

The element 39 is held in position by means of 35 the hooks 48 which engage the lugs 49 formed on the inner side of the wall 24 when the elements 24 and 39 are rotated with relation to each other in one direction and are prevented from becoming disengaged by rotation in an opposite direction by means of a headed pin 50 which extends downwardly through the element 39 on the opposite side of the next adjacent lug 49.

Secured to the outer side of the walls 16 are 40 the upwardly extending brackets 51 whose upper ends 52 occupy the recesses 53 in the outer rim 54 from which extend inwardly the radial arms 55, whose upper edges 56 are spaced below the under edges 57 of the arms 40. Resting upon 45 the upper edges 56 of the arms 55 is an annular outer ash ring 58, whose outermost edge 59 is spaced from the innermost surface 60 of the outer rim 54. The edges 59 and 61 of the outer ash ring 58 are preferably undercut, as shown.

On the underside of the outer ash ring 58 50 are formed the notches 62 which engage the arms 55 and serve to prevent the rotation of the ring 58 as well as to hold same concentric with relation to the outer portion 46 of the element 39. Between the inner edge 61 of the ash ring 58 and the outer portion 46 of the element 39 and also resting upon the arms 55 is an inner 55 adjustable ash ring 63, whose innermost edge 64 is parallel with the outer surface of the portion 46 and is vertically slidable with relation thereto.

The underside of the ring 63 is provided with 60 a series of notches 65, 66, 67, 68 and 69 of increasing depth making it possible to secure various adjustments for the elevation of the inner ring 63, whose outermost edge 70 is undercut. The ring 63 may be adjusted vertically by rotating same circumferentially until one of the desired notches 65 to 69 engages its respective arm 55. It will be noted that the inner edge 64 of the ring 63 extends downwardly sufficiently far when the ring 63 is in its lowermost position to cover the ports formed by the notches 47 and the tuyère wall 24.

It is desirable to surround the rim 54 with a

refractory material 71 which extends downwardly to the floor line forming an ash well 72 into which the ash duct end 32 extends.

The operation of the device is as follows:

Assume that the stoker is being operated and 5 that coal is being fed through the fuel feed duct 11 by the worm 12 into the retort 15 from whence it passes upwardly within the walls 34 of the tuyère element. As the fuel passes the outlets 45 and receives air therefrom in the presence of 10 the heat being generated about same, combustion begins fairly close to the center of the retort and as the burning coals are moved outwardly by the upwardly fed stream of green coal, the partially burned coal passes over the 15 element 39 across the intervening space 73 between the elements 39 and 63 which is negligible and across the space 74, which is variable depending upon the position in which the element 63 is placed upon the arms 55, after which 20 the almost completely burned fuel moves outwardly to the space 75 between the outer ash ring 58 and the rim 54.

It will be borne in mind that while this is taking place, the element 39 with its supporting 25 wall 34 and radiating arms 40 are all rotating due to the action of the worm 27 upon the wheel 26, and that during this rotation, air is passing to the arms 40 cooling and protecting same and at the same time affording additional combustion air to material resting on the ash rings 58 and 63. Obviously, the proportion of air being delivered through the outlets 45 in relation to the amount and pressure of air delivered through the spaces 74 and 75 will vary according to the 35 position of the inner adjustable ash ring 63.

In other words, air is supplied to the burning fuel close to the center of the combustion zone and is delivered in annular rings of increasing diameter toward the outer edge of the combustion zone, and the amount and pressure of the air thus delivered may be easily adjusted to suit 40 the operating conditions.

It will also be noted that by providing this 45 large burning area, it is less necessary to force the fire and it is therefore possible to avoid temperatures which would otherwise fuse the incombustibles and thereby produce clinkers which must either be broken up mechanically or removed manually. By the construction above described, clinkers are not formed and the resulting ash is of a very fragile nature making it possible for it to easily escape downwardly through the spaces 74 and 75 by gravity or with the aid of the air blown through the arms 40 or by an agitation set up through the movement 55 of the arms themselves.

I claim:

1. An underfeed stoker having in combination a revolvable tuyère section comprising spaced 60 circular inner and outer walls, a retort including means for discharging fuel upwardly through the retort into the tuyère section, means for admitting air to the space between the tuyère walls, the outer tuyère wall having air discharge openings therein, said revolvable tuyère section having radial arms projecting horizontally from the top edge thereof, each of said arms having an air passage communicating with the interior of the tuyère section and having a discharge opening on the under side thereof, a stationary ash ring concentrically spaced from said tuyère section, a vertically adjustable ash ring disposed within the space between the tuyère section and the stationary ash ring, said vertically adjust- 65 70 75

able ash ring constituting a means for controlling the flow of air through the outermost tuyère openings and through the annular space between said ash rings.

5. 2. An underfeed stoker having in combination a revolvable tuyère section having a toothed ring attached thereto, an ash removing worm meshing with said toothed ring, means for driving said worm, the upper portion of said tuyère section having a cylindrical exterior provided with air outlets, a vertically adjustable ash ring disposed around said cylindrical tuyère portion adapted to control the flow of air through said outlets, a stationary ash ring disposed outside of said vertically adjustable ash ring, the adjacent edges of said ash rings being beveled in a manner to vary the clearance between same when said adjustable ring is moved vertically and a retort disposed under said tuyère section having means 20 for discharging coal upwardly therethrough.

3. An underfeed stoker having in combination a revolvable tuyère section comprising concentric spaced inner and outer walls, said tuyère section having a toothed ring attached thereto, an ash removing worm meshing with said toothed ring, means for driving said worm, the upper portion of said tuyère portion having a cylindrical exterior provided with air outlets, a vertically adjustable ash ring disposed around said cylindrical tuyère portion adapted to control the flow of air through said outlets, a stationary ash ring disposed outside of said vertically adjustable ash ring, the adjacent edges of said ash rings being beveled in a manner to vary the clearance between said ash rings when said adjustable ring is moved vertically and a retort discharging upwardly into said tuyère section.

4. An underfeed stoker having in combination a revolvable tuyère section comprising spaced circular inner and outer walls, said tuyère section having a toothed ring attached thereto, an ash removing ring meshing with said toothed ring, means for driving said worm, the upper portion of said tuyère section having a cylindrical exterior provided with air outlets, a vertically adjustable ash ring disposed around said cylindrical tuyère portion adapted to control the flow of air through said outlets, a stationary ash ring disposed outside of said vertical adjustable ash ring, the adjacent edges of said ash rings being beveled and a plurality of radial arms projecting outwardly from the inner upper edge of said tuyère section and

provided with channels communicating with the interior of the tuyère section and discharging downwardly upon said ash rings.

5. A stoker having a retort and means for feeding fuel upwardly therethrough, a revolvable circular tuyère section comprising concentrically spaced inner and outer walls disposed immediately above the level of the discharge opening of said retort, the outer side of said tuyère section being cylindrical and perforated, an annular adjustable 10 ash ring disposed around the cylindrical portion of said tuyère section constituting a means for varying the flow of air through its perforations, a stationary ash ring disposed around the adjustable ash ring and spaced therefrom, a rim supporting said stationary ash ring and projecting upwardly therefrom, a toothed ring attached to said tuyère section and an inclined ash removing worm meshing with said toothed ring.

6. A stoker having in combination a tuyère section comprising spaced circular inner and outer walls, the inner walls constituting the upper portion of a retort and the space between the inner and outer walls constituting an air supply chamber, said outer wall having air outlets therein, 25 an adjustable ash ring disposed around said outer wall adapted to be adjusted vertically for the purpose of controlling the flow of air through said outlets and means for rotating said inner and outer walls.

7. An underfeed stoker having in combination a circular revolvable tuyère section having spaced inner and outer walls, said tuyère section having an open underside for the admission of air to the space between said walls, said tuyère section having air discharge openings in its inner and outer walls, said tuyère section having radial arms projecting horizontally outward from the top edge thereof, each of said arms having an air passage communicating with the interior of the tuyère section and having a discharge opening on the underside thereof, a retort discharging upwardly into said tuyère section, means for feeding fuel upwardly through the retort, a stationary ash ring concentrically spaced from said tuyère section and a vertically adjustable ash ring disposed within the space between said tuyère section and stationary ash ring, said vertically adjustable ash ring constituting a means for controlling the flow of air through the outermost tuyère openings and through the annular space between said ash rings.

HASKELL C. CARTER.
